Attorney

UNITED STATES PATENT OFFICE.

AARON S. NEWMARK, OF NEW YORK, N. Y.

FOLDING TOOL.

Application filed January 4, 1926. Serial No. 79,130.

To all whom it may concern:

Be it known that I, AARON S. NEWMARK, a citizen of the United States of America, residing at city, county, and State of New York, have invented a new and useful Folding Tool, of which the following is a specification.

My invention relates particularly to handles for implements such as saws, brushes, combs, rulers, fish rods, etc.

The main object is to provide a simple device for securely holding or locking the parts of a folding handle in the extended position.

Another object is to facilitate the locking and unlocking action.

For these purposes I provide the central section of the handle with two locking bolts between which is mounted a transmitting gear. One of these elements is provided with a projecting operating member.

Fig. 1 is a side view showing in dotted lines the handle extended and locked.

Fig. 2 is an edge view showing the handle folded up.

Fig. 3 is a cross sectional view taken through the central part.

The central section 5 has the two end sections 6 and 7 hinged to it at 8 and 9 on opposite sides. Reinforcing side plates 10 are preferably provided and held in place for instance by means of rivets or screws 11. The end sections may likewise be reinforced by side plates 12 and 13 held in place suitably for instance by rivets or screws 14 and 15. The hinge sections may be formed integrally with the side plates.

The locking bolts 16 and 17 are carried by the central section 5 and adapted to be slid back and forth for instance by a projection such as 18 or 19 so that they can be housed in the central section or have their ends projected into corresponding recesses

in the end members. Between the bolts 16 and 17 I mount a transmitting member 20 which is pivoted on the stud 21 between the side plates. This is geared preferably by teeth to the bars 16 and 17 so that when either bar 16 or 17 is moved the other moves with it.

The gear 20 may have an external operating knob 22 and in such case the end member 6 may have a recess 23 for the knob 22 when the device is folded up. Only one projecting operating member however is required.

The device may have a lateral extension 24 or an end extension 25 depending upon the character of work to be done by the device.

I claim:

1. A folding tool comprising a central section, an end section hinged to each end of said central section, a rotatable gear carried by the central section, and bolts having teeth meshing with said gear and adapted to engage the end sections when protruded from the central section.

2. A folding tool comprising a central section, an end section hinged to each end of said central section, bolts carried by said central section and adapted to engage the end sections, one of said bolts having a projecting operating member, and a rotatable member carried by the central section for transmitting motion from one bolt to the other.

3. A folding tool comprising a central body section, end sections hinged thereto, side plates reinforcing said sections and providing hinge members, a locking device carried by said central body section and consisting of bolt members and a transmitting gear member, one of said members having a projecting operator, said plates forming housings for said members.

AARON S. NEWMARK.
